ARTIFICIAL FISH BAIT

Richard Owen Porter, Sr., Daytona Beach, Fla.

Application July 14, 1953, Serial No. 25,951

Term of patent 14 years

(Cl. D31—4)

FIG. 1

FIG. 2

FIG. 3

FIG. 4

To all whom it may concern:

Be it known that I, Richard Owen Porter, Sr., a citizen of the United States, residing at 222 3rd Avenue, city of Daytona Beach, in the county of Volusia and State of Florida, have invented a new, original, and ornamental Design for Artificial Fish Baits, of which the following is a specification, reference being had to the accompanying drawing, forming a part hereof.

Figure 1 is a top plan view of an artificial fish bait, showing my new design.

Figure 2 is a side elevation thereof.

Figure 3 is a bottom plan view thereof.

Figure 4 is a head end plan view thereof.

I claim:

The ornamental design for an artificial fish bait, as shown.
